UNITED STATES PATENT OFFICE.

JOHN FRANCIS GALBRAITH, OF SHELBYVILLE, TENNESSEE.

SHEET-METAL ROOFING.

No. 877,639.

Specification of Letters Patent.

Patented Jan. 28, 1908.

Application filed September 13, 1906. Serial No. 334,509.

To all whom it may concern:

Be it known that I, JOHN FRANCIS GALBRAITH, of Shelbyville, in the county of Bedford and State of Tennessee, have invented 5 a new and useful Improvement in Sheet-Metal Roofing, of which the following is a specification.

My invention has to do with the joint between metal roofing shingles or plates, the 10 object primarily being to obtain a joint which is weather proof, non-leaking, of great strength and durability, and requiring the minimum of material for its formation.

A further object is to form the joint so 15 that the same may be applied to both edges of the shingle, thus permitting it to be used in working either to the right or left—in other words permitting the work to be started at any point between the eaves and comb 20 of a roof and thence to be carried on both to the right and left of that point, one man working to the right and the other to the left.

The invention will first be described in connection with the accompanying drawings 25 and will then be more particularly pointed out in the claim.

In the drawings, Figure 1 is a perspective view of several joined sheet metal roofing shingles embodying the invention. Fig. 2 is 30 an end elevation of one of these shingles, to illustrate more clearly the symmetrically formed opposite edges.

The shingle A, as indicated, has on each edge a border h adapted to serve as either 35 a mailing edge or tongue member of the joint, as the case may be, a member of approximately inverted V form in cross section (composed of legs i j) which constitutes the cap member of the joint, and a bead x between the border h and the cap member.

The two edges are symmetrical.

The cap member is formed by folding and pinching together the sheet metal of the shingle to form a solid flange of double thickness and then bending this flange into approximately inverted V form as shown. The inclined front leg i of the cap member is that under and against which the tongue h of the next adjoining plate rests. The rear inclined 45 leg j of the cap member springs from the face of the shingle; and within the cap member, back of and below the meeting faces of the members of the joint, is a valley g which receives any moisture that may form in or en-

55 ter the joint, and serves not only to ventilate the joint but also as a permanent drain or way through which all moisture or water which may pass beyond the meeting faces of the members of the joint can be at once carried off. The border h forms the tongue member 60 of the joint when it overlaps the edge of the adjoining shingle. But when it is overlapped by and lies beneath the adjoining shingle it forms the "nailing edge", so called. Thus according to its position it serves in either 65 one or the other of these two capacities. When two shingles thus formed are connected together as shown in Fig. 1, it will be noted that the interlocking cap-joint is thoroughly shielded from rain driving in either direction; there 70 is practically no possibility of leakage into the interior beyond the bead x; and there is provided within the cap member a permanent open valley g beyond and beneath the joint to catch and at once carry off any water which 75 may percolate therethrough. It will also be noted that by making both edges of the shingles symmetrical as shown, it is possible with such shingles to work from the left or from the right of any one shingle with equal facility, thus permitting two workmen to work 80 simultaneously from the same point, but in opposite directions.

Having set forth my improvement and the best way now known to me of carrying the 85 same into practical effect I state in conclusion that I do not limit myself strictly to the structural details herein shown and described in illustration of my invention, since manifestly the same can be varied in a number of particulars 90 without departure from the spirit of my invention; but

What I claim herein as new and desire to secure by Letters Patent is as follows:

A roofing plate or shingle having symmetrically formed opposite edges, each formed with a border h adapted to serve as a tongue or "nailing edge" as the case may be, a cap member i, j, of substantially inverted V form in cross section and a bead x between the border and the cap member, as and for the purposes hereinbefore set forth.

In testimony whereof I affix my signature in presence of two witnesses.

JOHN FRANCIS GALBRAITH.
